UNITED STATES PATENT OFFICE.

CHRISTIAN O. OSTBYE, OF PROVIDENCE, RHODE ISLAND, ASSIGNOR TO THE GORHAM MANUFACTURING COMPANY, OF SAME PLACE.

DESIGN FOR A SPOON.

SPECIFICATION forming part of Design No. 27,235, dated June 22, 1897.

Application filed May 6, 1897. Serial No. 635,429. Term of patent 7 years.

To all whom it may concern:

Be it known that I, CHRISTIAN O. OSTBYE, a citizen of the United States, residing at Providence, in the county of Providence and State 5 of Rhode Island, have invented and produced a new and original Design for a Spoon or Similar Article, of which the following is a specification, reference being had to the accompanying drawings, forming part thereof.

Figure 1 is a view of the obverse side of a spoon, showing my design. Fig. 2 is a view of the reverse side of the spoon.

The leading features of my design consist in the representation of arctic scenes on the 15 handle, surmounted by a geographical globe, and the representation of ships in the bowl, presenting to the eye a graphic illustration of the late arctic explorations by Nansen in the ship called the "*Fram*."

In the drawings, A indicates the bowl of the spoon, B the stem of the handle, and C the blade at the upper end of the handle. The bowl of the spoon has the conventional 20 oval outline, and in the bowl is formed the representation of a rigged ship resembling the ship named the "*Fram*," in which Dr. Nansen made his late exploring expedition. Smaller ships accompany the central larger vessel. The handle at the point of connection with the bowl contracts to the point d and from this point gradually increases in 25 width to the point e, where it curves outward

and upward to form the lower end of the blade C, curving slightly inward and then outward. The margin of the blade C extends upward 35 in curved lines, terminating at the point f and is surmounted by the semicircular end g.

On both the obverse and the reverse of the handle the marginal lines are formed into raised beads, the lower parts of which resemble the runners of an arctic sleigh, and the upper parts resemble branches of the horns of arctic deer or the moose. The front of the handle is ornamented at its upper end with a representation of a geographical globe, 40 the lower part of which has the bust of a man above two branches of laurel. An arctic scene ornaments the rest of the handle.

The rear of the handle, as shown in Fig. 2, has at its upper end a conventional view of 45 an arctic landscape. The stem of the handle is ornamented with two arctic sleigh-runners.

Having thus described my newly-produced 50 design, I claim as new and desire to secure by Letters Patent—

The design for a spoon or similar article 55 herein shown and described.

In witness whereof I have hereunto set my hand.

CHRISTIAN O. OSTBYE.
